UNITED STATES PATENT OFFICE.

ELMER L. SCHUMACHER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

ZYL-COVERED SEPARABLE END PIECE.

Application filed August 22, 1924. Serial No. 733,526.

To all whom it may concern:

Be it known that I, ELMER L. SCHUMACHER, a citizen of the United States, residing at Southbridge, in the county of Worcester and State of Massachusetts, have invented certain new and useful Improvements in Zyl-Covered Separable End Pieces, of which the following is a specification.

Heretofore it has been the customary practice to cover solid end pieces of spectacle frames, either by painting, dipping, or otherwise applying a composition, preferably zyl or zylonite, hence there is no claim made for the broad idea of a covering of this character and the manner by which the covering is applied.

However, a covering such as used on solid end pieces has been found unsatisfactory for use in connection with divided or separable end pieces, as such covering would encase both sections or members of the end piece and prevent access to the two members thereof, when it is necessary to make repairs.

In view of the above, and in connection with a divided or separable end piece, it is the purpose of the present invention to provide individual coverings for the separable elements of the end piece, to permit the elements to be detached from each other to allow the rim to open or spring apart, either for the repair of the lens or for the repair of the elements of the end piece, or the repair of the coverings.

Another purpose is the provision of recesses on opposite portions of the adjacent faces of the elements of the end piece to receive marginal portions of the coverings to retain the latter in place.

Still another purpose is to provide a blank of fiber, preferably zyl or zylonite, which may be fitted to each of the elements of the end piece, suitably heated and pressed in order to conform to the contour of the element of the end piece.

A further purpose is to provide a blank, preferably of zylonite, in which an imprint of the shape of an end piece element is formed for facilitating centering the end piece element relatively to the blank.

A still further purpose is to provide zyl receiving cavities in opposite portions of each element to receive the zyl or other composition covering, which is subjected to heat

and made pliable, whereby the composition may conform to the shape of the element.

The invention further aims to employ struck up tangs or projections on the sides of each end piece element, in lieu of cavities or recesses, the fiber covering adapted to be heated, so that when the covering takes the form of the end piece element it will also cooperate with the tangs or projections and thereby retain the covering in position.

It is to be understood that the particulars herein given are in no way limited, and that still keeping within the scope of the invention, any desired modifications of detail and desired proportions may be made in the end piece construction and the coverings therefor according to circumstances.

The invention comprises further features and combinations of parts as will be herein-after set forth, shown in the drawings, and claimed.

In the drawings:

Figure 1 is a perspective view of a pair of spectacles showing the improved separable end piece applied, and constructed in accordance with the invention;

Figure 2 is an enlarged perspective view of a portion of one of the rims of the spectacle frame, also disclosing the separable end piece suitably covered with zyl;

Figure 3 is a sectional view on line 3—3 of Figure 2;

Figure 4 is a sectional view on line 4—4 of Figure 2;

Figure 5 is a perspective view of one of the elements of the separable end piece, showing where the element is cut away for the reception of the hinge ear of the temple, and also showing the folded parts of the covering;

Figure 6 is a plan view of a blank of zyl or other fiber material, showing the imprint of the shape of an element of an end piece, whereby the end piece may be centered during the process of applying the covering;

Figure 7 is a sectional view through a modified construction of end piece, wherein the coverings are retained in position by means of tangs;

Figure 8 is a perspective view of one of the elements of the separable end piece shown in Figure 7;

Figure 9 is a sectional view on line 9—9 of Figure 8, showing additional tangs.

Referring to the drawings, 1 designates a conventional spectacle frame, comprising the rims 2 and the nose bridge 3. The rims 2 may be zyl covered, as shown, and their remote portions have separable ends 4, which terminate in lateral end piece elements 5 and 6. The end piece elements 5 and 6 are parallel and may be any shape or contour and any proportions. Preferably the end piece elements extend laterally and rearwardly, and their adjacent faces in close position to the terminals of the end pieces are provided with recesses or cut away portions 7 and 8, which, when the end piece elements are secured together, receive the hinge ear 9 of a temple 10.

The hinge ear has a central opening 11, through which a pivot pin 12 (which rises from the bottom of the recess or cut away portion 8 extends, thereby pivotally mounting the temple. This pivot pin 12 additionally serves to hold the end piece elements in register, due to the fact that it extends into and fits a cavity 13 constructed in the bottom of the recess or cut away portion 7 of the end piece element 5.

The greater portion of each end piece element is provided with cavities or recesses 14, which are substantially angular in contour, shown clearly in Figure 4. These recesses or cavities 14 are adjacent opposite edges and the adjacent faces of the end piece elements.

The end piece elements are provided with coverings 15, which may be constructed of any suitable fiber, preferably zyl or zylonite, and in applying the covering it is first constructed in a blank, as disclosed in Figure 6. This blank receives an imprint, such as shown at 16, of the shape of an end piece element, the blank beyond the margin of the imprint having sufficient material 17 to be bent and pressed up against the sides of the end piece element. To conform to the recessed or cut away face of the end piece element, the additional material of the blank, that is, beyond the imprint 16, is cut away as at 18. In applying the covering, which is in the form of a blank, as shown in Figure 6, the blank is subject to heat, sufficient to render the blank pliable. Then the additional or excess material 17 is bent and pressed up against the sides of the end piece element, and the marginal portions of this additional material are pressed over and forced into the recesses or cavities 14, thereby retaining the covering in position. The zyl in its heated pliable condition readily conforms to the contour of the end piece, regardless of its shape. The end piece elements are fastened together detachably by means of a screw 19, which is threaded through the adjacent end piece elements, as shown clearly in Figures 2, 3 and 4. The

head of the screw is countersunk in the zyl, and the face of the head is flush with the exterior of the zyl.

The blank in Figure 6 may be imprinted and stamped by any suitable means, preferably a suitable die.

Referring to Figure 7, 8 and 9, the covering or blank is similarly constructed and applied, with the exception that the excess material of the blank, that is, beyond the imprint of the shape of the end piece element, is not disposed to overlie the inner face of the end piece element. In order to secure the covering to the end piece element, shown in Figures 7, 8 and 9, the sides of the element are provided with up-struck tangs or projections 20. The excess material, that is, beyond the imprint of the end piece element in the blank, when applying the covering or blank to the construction of end piece element in Figures 7, 8 and 9, is heated and pressed in close contact with the sides of the end piece element. The material cooperates with the tangs to secure the covering in position. In this manner it is not necessary to recess the end piece elements, as in Figures 1 to 5 inclusive.

The invention having been set forth, what is claimed is:

1. The combination with separable end piece elements provided with opposed recesses for the reception of a temple hinge ear, said elements having covering, receiving and attaching cavities, of composition coverings for said elements, engaged in the said receiving and attaching cavities, means for pivotally supporting the hinge ear of a temple in said opposed recesses, and means for fastening said end piece elements together.

2. In a device of the character described, an end piece comprising two metallic members separable on a line of joinder and having marginal recesses adjoining the line of joinder and a non-metallic covering over each metallic member having a portion extending into and retained in the marginal recess with clearance for the metallic members to abut on the line of joinder.

3. In a device of the character described, a metallic end piece member having a marginal recess in one face and a non-metallic covering over the other face and the edges of said metallic member extending into and retained in the marginal recess of the recessed face.

4. In a device of the character described, a metallic end piece having a recessed portion and a non-metallic covering over one face and edges of said metallic end piece extending into and retained in the recessed portion of the end piece.

ELMER L. SCHUMACHER.
